United States Patent Office

Des. 183,876
Patented Nov. 11, 1958

183,876

FISH LURE

William R. Courtright, Detroit, Mich., assignor of one-half to Peter MacFadyen, Highland Park, Mich.

Application May 21, 1958, Serial No. 50,999

Term of patent 3½ years

(Cl. D31—4)

Fig. 1 is a top plan view of a fish lure embodying my new design;

Fig. 2 is a side elevational view;

Fig. 3 is a front elevational view; and

Fig. 4 is a rear elevational view.

I claim:

The ornamental design of a fish lure, substantially as shown.
